CUTTER FOR PANTOGRAPH ENGRAVING MACHINES

Martin H. Preis, Cranford, and Jakob A. Hoffmann, Lyndhurst, N. J., assignors to H. P. Preis Engraving Machine Co., Newark, N. J., a partnership consisting of Elizabeth J. Preis and Martin H. Preis

Application November 1, 1947, Serial No. 783,582

4 Claims. (Cl. 33—18)

1

This invention relates to improvements in cutters for pantograph engraving machines. It is the object of this invention to provide a cutter adapted to be inserted into the spindle or holder of such machine to enable the reproduction of lettering and other indicia in a form different in degree of thickness than that of the traced master copy type. The invention is especially adapted for use for cutting into name plates and the like, lettering of unique outline and containing gradations which are characteristic of script and similar types of lettering, while using only the conventional master copy type of uniform outline.

These and other advantageous objects, which will appear from the drawings, and from the description hereinafter, are accomplished by the structure of the invention, of which one embodiment is illustrated in the drawings. It will be apparent, from a consideration of said drawings, and the following description, that the invention may be embodied in other forms suggested thereby, and such other forms as come within the scope of the appended claims are to be considered within the scope and purview of the instant invention.

In the drawings:

Fig. 1 is a side elevational view of a cutter spindle of a form which may be used in carrying out the invention.

Fig. 2 is a side elevational view of a cutter embodying the invention.

Fig. 3 is an enlarged elevational view of the cutter tip, taken on line 3—3 of Fig. 2.

Fig. 4 is an enlarged elevational view thereof, taken on line 4—4 of Fig. 2.

Fig. 5 is a similar view, taken on line 5—5 of Fig. 4.

Fig. 6 is an enlarged fragmentary view of a section of the name plate which has been cut by the cutter of the invention.

Fig. 7 is a similar view, showing cut obtained on rotation of the cutter to a position 90° to that of which the cut of Fig. 6 was made.

Fig. 8 is an enlarged bottom plan view, taken on line 8—8 of Fig. 4, and

Fig. 9 is a fragmentary perspective view, schematically illustrating the method of operation of the pantograph mechanism, provided with a cutter embodying the invention.

In Fig. 2 of the drawings, there is shown one form of cutter embodying the invention, comprising an elongated tubular body member 10, provided with a cutting point or cutter tip 11 formed by cutting three faces into said tip at 30° angles to the longitudinal axis of the cutter, said

2

three faces being indicated in Fig. 8 by the reference characters 26, 27, 28, and being disposed with respect to each other as indicated by the lines 26a, 27a, 28a, said lines indicating the lines of intersection of a plane perpendicular to the longitudinal axis of the cutter with the faces 26, 27 and 28, respectively, and showing the right angular relationship of the intermediate line 27a with the adjacent and parallel lines 26a and 28a. 10 A fourth cut is made into the extreme tip of the cutter to provide a face 35 intersecting the faces 26 and 28 and terminating at the point 36. The line of intersection 29 between the faces 35 and 28 is as indicated in Figs. 4 and 5 at an angle of 15 10° to the projection line 38 which is drawn from point 36, which is the outermost point of the cutter, the projection line 38 lying in a plane perpendicular to the tool axis. The line of intersection between the faces 35 and 26 is, as indicated 20 by the projection line 39 in Figs. 4 and 5, at an angle of 5° with the line 29, thus making the total angle between the last named intersection line and the projection line 38, 15°. Thus the cutting portion of the cutter is defined by four 25 faces numbered 26, 27, 28, and 35, all of which are cut or lie in planes which are at acute angles with respect to the longitudinal axis of the cutter and intersect to provide a common point 36 lying in the axis of the cutter. It will be noted that the face 35 is relatively smaller in area than the remaining faces and that this face lies in a plane which intersects the adjacent faces 26 and 28 along lines which lie at different angles to a transverse plane passing through the point 36 and disposed perpendicularly to the axis of the 30 cutter. This provides desirable relief for the lower, substantially radial cutting edge of the face 35 as clearly shown in Fig. 5. By this arrangement, when the cutter is positioned with the face 28 thereof facing the direction of movement 35 of the cutter, the cutter will make a wide L-shaped cut 31 in the material of the name plate 24 or other object being cut. When the cutter is disposed so that the face 27 thereof is pointed in the direction in which the cutter is moved, said cutter will make a narrow V-shaped cut 32 as 40 shown in Fig. 7. Between the right angle separated positions of the cutter of Figs. 6 and 7, the cutter may be rotated to any intermediate position to cut the name plate 24 according to the position of the cutter with relation to the direction of movement thereof. If the cutter is moved in the direction faced by face 26 thereof, then a cut will be produced, which will, because of face 35, 45 be less shallow than the cut 31. Similarly, if the 50 55

3

rear face 37 of the cutter (Fig. 5) is pointed in the direction of movement of the cutter, a cut similar to cut 32 of Fig. 7 will be produced, but, because of face 35, of more shallow outline. The cutter is preferably made of relatively hard material, while the plate 24 may be made of a comparatively softer material. The cutter 10 is preferably provided with a flat portion 12 or the like, and is adapted to be inserted into recess 14 of cutter spindle or holder 13, the latter having an aperture 15 communicating with the recess 14 for a set screw 16 to bear against the flat portion 12 of the cutter, to lock the same in position (Fig. 9). The cutter spindle 13 may be provided with a handle 17 or the like to enable the same to be manually rotated if desired and may be positioned in the bracket 18 with the spring 34 disposed between a collar 13a on the cutter and the bracket 18, to normally hold the cutter just clear of the surface of the name plate 24 or very lightly bearing thereon. The bracket 18 is secured to the pantograph mechanism arm 19 which, as will be apparent to those skilled in this art, is connected to another pantograph mechanism arm 19', the latter being provided with a tracing style holder 20 in which the tracing stylus 21 is secured. The name plate 24, to be inscribed, is held by any suitable work-holding clamp 22 upon a work table 22'. The master copy type 23, to be reproduced, is positioned in a copy-holder slide 33, or the like. By this arrangement, the master copy type 23 may be reproduced on the name plate 24 at a different scale, as will be apparent to those skilled in the art.

The cutter body 10 may be fixed to the spindle or holder 13 secured to the pantograph mechanism arm 19 to provide variations in thickness of the lettering reproduced, as at 25, although the original or master type 23 is of uniform thickness. This is due to the fact that the cutter will be moved along different angles to the longitudinal axis of the plate 24 in the movement of the pantograph mechanism and by virtue of the different angular positions of the cutter, the cuts produced thereby (Figs. 6 and 7) will differ correspondingly. This result may be obtained automatically by fixing the cutter against rotation in the bracket 18.

If desired, the cutter holder 13 may be rotatably positioned in the bracket 18, as indicated in Fig. 9 and provided with a handle 17 or the like to facilitate the manual rotation thereof, whereby the user may rotate the cutter to provide gradations of width of the lettering 25 according to the degree he desires. Thus, by the use of a simple standard master copy type, it is possible to reproduce individually stylized lettering 25 on name plates 24. The term "lettering" as herein used, shall be deemed to include any indicia or design.

Having thus described our invention, what we claim as new and desire to secure by Letters Patent, is:

1. A cutter for pantograph engraving machines comprising an elongated cutter body, a cutting point on one end of said body, said cutting point being defined by three faces cut at an angle of 30° to the longitudinal axis of the cutter and angularly disposed with respect to each other so that a transverse section at right angles to the longitudinal axis of the cutter defines lines of intersection with said three faces such that two of said lines are each connected to the third

line by right angles, and a fourth face cut by a plane intersecting two of said three faces and the longitudinal axis of said cutter at an angle to define a line of intersection with one of said two faces which is substantially 10° to a projection line perpendicular to the axis of the cutter, and to define with the other of said two faces a line of intersection which is substantially 15° to said perpendicular projection line.

2. A cutter for pantograph engraving machines comprising an elongated cutter body, a cutting point on one end of said body, said cutting point being defined by three faces cut at a common acute angle with respect to the longitudinal axis 15 of the cutter and angularly related to each other so that a transverse section at right angles to the longitudinal axis of the cutter defines lines of intersection with said three faces such that two of said lines are each connected to a third 20 line by right angles, and a fourth face cut at an acute angle to a projection line perpendicular to the longitudinal axis of said cutter and intersecting two of said three faces along lines having different angular relations to said perpendicular projection line to provide a relieved cutting edge.

3. A cutter for pantograph engraving machines comprising an elongated cutter body, a cutting point on one end of said body, said cutting point being defined by three faces cut at a common 30 angle to the longitudinal axis of the cutter and angularly related to each other so that a transverse section at right angles to the longitudinal axis of the cutter defines lines of intersection with said three faces such that two of said lines are each connected to the third line by right angles, and a fourth face defined by a line of intersection between said fourth face and one of said three faces which line is at an angle of substantially 10° to a projection line perpendicular to the axis of said cutter, and a second line of intersection between said fourth face and another of said three faces which second line of intersection makes an angle of substantially 45 15° with said perpendicular projection line.

4. A cutter for pantograph engraving machines comprising an elongated cutter body, a cutting point on one end of the body, said cutting point being defined by four flat faces cut at acute 50 angles to the longitudinal axis of the cutter, said faces intersecting at a common point lying within the longitudinal axis of the cutter, one of said faces being relatively small in area in comparison to the areas of the other three faces, said face 55 of smaller area lying in a plane intersecting the planes of two adjacent faces along straight lines which are inclined at different angles to a transverse plane passing through said common point perpendicular to the axis of the cutter to thereby provide a relieved substantially radial cutting edge.
